DEVICE FOR HOLDING WIRES TAUT

Melburn A. Comeau, Haverhill, Mass.

Application May 2, 1934, Serial No. 723,587

10 Claims. (Cl. 173—313)

This invention relates to devices for holding wires taut and is particularly adapted for use as insulators for electric wires.

The object of the invention is the provision of means whereby the wire may be readily inserted into the support and between a plurality of slideable jaws in the bore of said support whereby the wire will be firmly gripped when the jaws are moved in one direction and released upon movement of the jaws in the opposite direction.

This object is attained by the mechanism illustrated in the accompanying drawing.

For the purpose of illustrating the invention, one preferred form thereof is illustrated in the drawing, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

25 Of the drawing

Figure 1 represents an elevation of a device embodying the principles of the present invention.

Figure 2 represents a vertical section of the same on line 2, 2, on Fig. 1.

Figure 3 represents a horizontal section on line 3, 3 on Fig. 2.

Figure 4 represents a partial vertical section on line 4, 4 on Fig. 3, drawn to an enlarged scale, the upper part of the closing cap being omitted.

Figure 5 represents a partial vertical section on line 5, 5 on Fig. 3, drawn to an enlarged scale, the closing cap being removed.

Figure 6 represents a vertical section on line 6, 6 on Fig. 4 and showing the closing cap.

Figure 7 represents a vertical section on line 7, 7 on Fig. 5.

Figure 8 represents a plan of the jaw separating device.

Figure 9 represents an elevation of the open spring to hold the jaws together, and

Figure 10 represents an elevation of the bore closing plate.

Similar characters indicate like parts throughout the several figures of the drawing.

In the drawing, 10 is a support preferably made of material non-conductive of electricity and having a threaded hole 11 in the bottom

thereof by which it may be attached to the usual pin on the crossbar of a telegraph pole.

The support 10 has extending transversely thereof a tapered bore 12, the larger end of which is closed by a plate 13 having vertical inturned flanges 14 entering grooves in a side face of said support 10.

This plate 13 has a hole 15 of less diameter than the larger end of the bore 12 and from this hole extends upwardly a radial slit 15x of 10 sufficient width to receive a wire W to be locked in said support 10.

Extending upwardly from the bore 12 and aligned with the slit 15x is a radial slot 16, the upper end of which is closed by a cap 17 having 15 inturned flanges 18 disposed in horizontal grooves in the side walls of the support 10.

Beneath the cap 17 and connected thereto is a tongue 19 adapted to be disposed within the slot 16, this tongue 19 having a downward projection 20 adapted to center the wire W in the center of the bore 12.

Within the bore 12 are a plurality of gripping jaws 21 slightly tapered to fit the bore 12.

These jaws 21 have near one end thereof a 25 groove 22 in which is disposed an open spring member 23.

The jaws 21 are of less length than the bore 12 and can be moved endwise within said bore, the taper of said bore preventing displacement of 30 said jaws 21 when moved in one direction while the plate 13 prevents displacement of said jaws when moved in the opposite direction.

The side jaws 21 are kept separated until the wire W is disposed between them by means of a 35 curved member 24 inserted between said jaws 21 so that the space between said jaws will register with the lower end of the slot 16.

This member 24 is provided with a downturned ear 24x by which the member 24 may be removed 40 from the jaws 21 after the wire W has been positioned in the bore 12, said member 24 being then thrown away.

When the wire W is to be disposed in the support 10 the cap 17 is removed.

The wire W may then be moved downwardly in the slit 15x and slot 16 until it is in the center of the bore 12 and between the side jaws 21.

The cap 17 is then positioned on the top of the support 10 closing the upper end of the slot and preventing rain or snow from entering the same.

When this has been accomplished and the tongue 19 is pressing down on the wire, the jaw separating device 24 is then removed permitting 55

the spring member 23 to force the jaws 21 into contact with the wire.

If the wire is then pulled towards the larger end of the bore 12, it will draw the jaws 21 toward that end of the bore and permit them to be slightly expanded so that the wire may be drawn endwise of said jaws.

When the wire is released the weight of the tautened wire will cause the jaws 21 to be moved toward the smaller end of the bore 12 and firmly grip the wire W so that said wire cannot move in the direction of the arrow A.

By this means a wire may be drawn taut and then held in its tautened position.

15 15 The tongue 19 when in the slot 16 bears against the shoulders 19x thereby preventing any upward movement thereof.

When inserting the jaws 21 into the bore 12 of the support 10, the plate 13 must be removed, 20 said plate being replaced in fixed position on the support 10 as soon as the jaws have been properly disposed in said bore.

Any slack in the wire W may be removed by pulling the wire in the opposite direction to that indicated by the arrow A, the jaws moving to the larger end of bore 12 and expanding to permit free movement of said wire.

As soon as the pulling strain is removed the weight of the wire will move the jaws to the opposite end of the bore 12 and the jaws 21 will grip securely on the wire and prevent further movement in direction of arrow A.

While the invention is primarily designed for use in holding taut electric wires, it is obvious that 35 the device may be used in retaining taut any other kind of wire or cable.

Having thus described my invention, I claim

1. The combination of a support provided with a transverse tapered bore and a radial slot extending therefrom to receive a wire; and wire-gripping means fitted to said bore and movable endwise therein to grip the wire when moved in one direction and release same when moved in the opposite direction, said gripping means being 40 separated opposite said slot sufficiently to receive a wire.

2. The combination of a support provided with a transverse tapered bore and a radial slot extending therefrom to receive a wire; wire-gripping jaws fitted to said bore and movable endwise therein to grip the wire when moved in one direction and release same when moved in the opposite direction; and a closing member for said slot provided with means for centering the wire 55 in said bore.

3. The combination of a support provided with a transverse tapered bore and a radial slot extending therefrom to receive a wire; a plurality of gripping jaws fitted to said bore and movable endwise therein; a device for separating said jaws until a wire has been inserted therein; and means 60 for holding said jaws together during their endwise movement.

4. The combination of a support provided with a transverse tapered bore and a radial slot extending therefrom to receive a wire; a plurality of gripping jaws fitted to said bore and movable endwise therein; a device for separating said jaws until a wire has been inserted therein; a periph-

eral groove in said jaws; and an open spring disposed in said groove.

5. The combination of a support provided with a transverse tapered bore and a radial slot extending therefrom to receive a wire; a plurality of gripping jaws fitted to said bore and movable endwise therein; a device for separating said jaws until a wire has been inserted therein; means for holding said jaws together during their endwise movement; and a plate secured to said support at 10 the larger end of said bore having a hole therethrough of less diameter than said larger end. 5

6. The combination of a support provided with a transverse tapered bore and a radial slot extending therefrom to receive a wire; a plurality of gripping jaws fitted to said bore and movable endwise therein; a device for separating said jaws until a wire has been inserted therein; means for holding said jaws together during their endwise movement; and a cap plate secured to said support 15 closing said slot and having a tongue for retaining the wire between said jaws. 20

7. The combination of a support provided with a transverse tapered bore and a radial slot extending therefrom to receive a wire; a plurality of gripping jaws fitted to said bore and movable endwise therein; a device for separating said jaws until a wire has been inserted therein; means for holding said jaws together during their endwise movement; and a cap plate slidably secured to 30 said support closing said slot and having a tongue for retaining the wire between said jaws.

8. The combination of a support provided with a transverse tapered bore and a radial slot extending therefrom to receive a wire; a plurality of gripping jaws fitted to said bore and movable endwise therein; a device for separating said jaws until a wire has been inserted therein; means for holding said jaws together during their endwise movement; and a cap plate secured to said support 40 closing said slot and having a U-shaped tongue disposed between two of said jaws and separating them.

9. The combination of a support provided with a transverse tapered bore and a radial slot extending therefrom to receive a wire; a plurality of gripping jaws fitted to said bore and movable endwise therein; a device for separating said jaws until a wire has been inserted therein; means for holding said jaws together during their endwise movement; and a cap plate secured to said support closing said slot and having a tongue for retaining the wire between said jaws, said cap plate having inturned side flanges disposed in depressions in said support. 45 50 55

10. The combination of a support provided with a transverse tapered bore and a radial slot extending therefrom to receive a wire; a plurality of gripping jaws fitted to said bore and movable endwise therein; a device for separating said jaws until a wire has been inserted therein; means for holding said jaws together during their endwise movement; and a plate secured to said support at the larger end of said bore and having a hole therethrough of less diameter than said larger end, said plate having inturned flanges disposed in parallel grooves in said support. 60 65
